United States Patent Office

Des. 223,161
Patented Mar. 21, 1972

223,161

MULTIPLE STEREO SPEAKER UNIT FOR AUTOMOTIVE USE

Jonas H. Anchel, Milford, Pa., assignor to Sparkomatic Corporation, Milford, Pa.

Filed Oct. 28, 1970, Ser. No. 25,699

Term of patent 14 years

Int. Cl. D14—01

U.S. Cl. D26—14

Fig. 1

Fig. 5

Fig. 2

Fig. 4

FIG. 1 is a front perspective view of a multiple stereo speaker unit for automotive use embodying the inventor's design.

FIG. 2 is a front and bottom perspective view of the same.

FIG. 3 is a right side elevational view of the same.

FIG. 4 is a rear elevational view of the same.

I claim:

The original and ornamental design for a multiple stereo speaker unit for automotive use, as shown.
